Albert T. Rice

UNITED STATES PATENT OFFICE.

DAVID R. HENDERSON AND ALBERT H. HILL, OF ARKANSAS CITY, KANSAS; SAID HENDERSON ASSIGNOR OF HIS INTEREST TO EARL H. SLEETH, OF ARKANSAS CITY, KANSAS.

APPARATUS FOR HANDLING SLUDGE ACIDS.

Application filed July 30, 1921. Serial No. 488,744.

This invention relates to apparatus for handling thick sludge acids and more particularly to means for transferring the sludge acids.

5 Other objects of the invention will appear upon consideration of the following detail description and accompanying drawings, wherein the figure is a longitudinal section through the pumping apparatus.

10 Referring to the drawing 5 indicates a sludge softening tank and which is connected with the upper end of a spout 9. The spout 9 is generally cone or funnel shaped and is connected at its lower end with the 15 end of a cylinder 15 through the top side thereof. The transverse sectional area of the cylinder 15 is greater than the transverse sectional area of the spout 9 at the point where it communicates with the interior of the said cylinder.

20 The pumping apparatus includes the intake cylinder 15 which is connected with the discharge spout 9 leading from the softening tank 5. This intake cylinder is pro-

25 vided with a piston 16 adapted to reciprocate therein and the piston is connected to a hollow piston rod 17 which passes through a stuffing box 18 in the end of the cylinder 15 and is connected to the piston 30 16 as shown. The piston 16 is provided with a relatively large conical mouth 19 in communication with the interior of the hollow piston rod 17. The discharge cylinder 20 receives the opposite end of the hollow

35 piston rod 17, this piston rod passing through a stuffing box 21 on the end of the discharge cylinder. An air chamber 22 is in communication with the interior of the discharge cylinder 20, and this cylinder is 40 connected with a four inch discharge pipe 23 which is conducted to any suitable discharge point where the sludge may be discharged.

45 Intermediate the ends of the hollow piston rod 17 a steam cylinder 25 is provided through which the piston rod passes and receives a steam piston 26 which is adapted to be actuated by the steam passing into the cylinder at regular intervals through the

50 medium of the operation of the steam valve 27 so that the piston 26 will be reciprocated for causing a reciprocatory movement to be

imparted to the hollow piston 17. Actuation of the valve mechanism 27 is controlled by a connection 28 between the piston and the valve stem 29 in a manner well known in the art.

55 The operation of the apparatus is as follows. The sludge acids are likely to become quite thick in the storage tanks, particularly in cold weather and although capable of flowing through large pipes they are too thick to permit easy distribution through smaller pipe lines. Therefore 60 means are provided whereby these liquids pass through a large pipe from a main storage tank into a heating tank and are there heated by means of steam or the like and from which they are caused to flow into a cylinder having a piston movably mounted therein. When this piston moves towards the head end of the cylinder the oil or liquid is naturally forced towards the center of the piston and flows through the bore therein. A small amount of the oil 65 or acid is forced upwardly into the spout 9, but the amount traveling in this direction will be negligible as the oil or acid in this case is traveling against gravity and the tendency of the piston compressing the oil and forcing it through the supply pipe would result in the greater portion of the oil traveling through the supply pipe and into the distributing cylinder.

70 75 80 85 What is claimed is:

Apparatus for handling sludge comprising a cylinder having at its opposite side and at one end a spout which communicates with the interior of the cylinder through an opening, the transverse sectional area of which is less than the diametrical transverse sectional area of the cylinder, a hollow piston mounted for sliding movement in the cylinder, a hollow piston rod connected with the piston, means for reciprocating the piston rod, a distributing cylinder slidably receiving one end portion of the rod both of the said cylinders being approximately of the same transverse sectional area.

90 95 100 In testimony whereof, we have affixed our signatures.

DAVID R. HENDERSON.
ALBERT H. HILL.
